E. F. CLARK

YARN SPOOL BEARING

Filed May 16, 1923

UNITED STATES PATENT OFFICE.

EUGENE F. CLARK, OF LEAKSVILLE, NORTH CAROLINA.

YARN-SPOOL BEARING.

Application filed May 16, 1923. Serial No. 639,435.

To all whom it may concern:

Be it known that I, EUGENE F. CLARK, a citizen of the United States, residing at Leaksville, in the county of Rockingham, State of North Carolina, have invented certain new and useful Improvements in Yarn-Spool Bearings; and I do hereby declare the following to be a full, clear, and exact description of the invention, such as will enable others skilled in the art to which it appertains to make and use the same.

In a loom for weaving a tufted fabric, such as an Axminster carpet, spool-frames are used to carry spools upon which are wound the different yarns, these frames being carried into use in the loom upon carrying-chains.

It has been found that when one of the end clamps, which connects and supports the spool-frame on the chain, becomes bent or broken to such an extent that the frame will drop from the chain, the end bearing of the spool falls away from the spool, thus permitting the spool to drop, and thereby causing great damage, and loss of time. Furthermore, to repair the end clamp, it is necessary to remove the end bearing of the spool, thus causing great inconvenience, loss of time, and injury to the pattern of the fabric.

It is the particular object of the present invention to provide an end clamp, and an end bearing, which are independently mounted on the tube or quill frame or beam, with the result that should the clamp break or bend to such an extent as to cause it to leave the carrying-chain, the end bearing will remain properly engaged with the end spindle of the tuft spool. Furthermore, the end clamp can be readily and easily removed from the tube frame, without disturbing the end bearing.

Other objects and advantages will be apparent from the following description when taken in connection with the accompanying drawing.

In the drawing:

Figure 1 is a front elevation of a frame showing the end clamps and end bearings, the tube beam and tuft spool being centrally broken away.

Figure 2 is an end view of the same.

Figure 3 is a vertical sectional view on the line 3—3 of Figure 2.

Figure 4 shows the end clamp and end bearing, in perspective, in withdrawn posi-

tion from the tube beam, and slightly separated from each other.

Referring particularly to the accompanying drawing, 10 represents the tube or quill beam, which, as illustrated in the accompanying drawing, is a tube rectangular in cross section, and having the yarn guiding tubes or quills 11 secured to its front vertical face. The end bearings are each represented, as a whole, by the numeral 12, and consists of an angle plate having the wings 13 and 14, the former of which is disposed within the end of the tubular beam 10, while the latter is provided with a bearing eye 15, on its upper end for the supporting reception of the pintle 16 of the end of the yarn spool 17, which spool is disposed above and in parallel relation to the beam 10. Formed on the lower face of the angular plate 12, and depending therefrom in parallel relation, are the walls 18, each having the open-ended slot 19 in its rear vertical edge. In the wings or walls 18, forwardly of the inner ends of the slots 19, there are formed the threaded openings 20, which align transversely of the device. The walls 18, as clearly seen in the sectional view, Figure 3, are disposed within the end of the quill beam 10.

The end clamp includes an angle plate 21, having the horizontal wing 22, which is disposed within the end of the beam 10, and beneath the walls 18, and the vertical wing 23, which extends upwardly against the outer face of the vertical wing 14, of the end bearing 12. The upper end of the wing 23 is offset outwardly and upwardly, as at 24, for engagement with the carrying chain. (Not shown.) Formed in the angle of the plate 21, and disposed slightly inwardly from the side edges of the wings 22 and 23, are the vertical parallel walls 25. By spacing these walls 25 inwardly from the sides of the plate 21, said walls are arranged to pass inwardly between the walls 18 of the plate 12, as shown in the drawing. Formed in the walls 25, and in transverse alignment, are the threaded openings 26. In the opposite side walls of the quill beam 10, there are formed the threaded openings 27 and 28, for registration, respectively, with the openings of the angle plate 12, and of the angle plate 21. It will be noted that when the two angle plates are properly disposed in the end of the beam 10, that the slots 19 are in alignment with the openings 27, to

permit the retaining screw 29 to pass therethrough and through the walls 25, whereby the end clamp will be firmly held in the beam 10. In the other openings 28 a retaining screw 30 is engaged, to hold the end bearing within the beam. Should the end clamp break or bend to a sufficient extent to permit the same to become disengaged from the carrying chain, the end bearing will not be disturbed, and the screw 29 removed, to take out the clamp for repairs or replacement. Thus all danger of the end of the yarn spool falling from the frame is obviated, as the end bearing thereof will remain securely within the beam 10 by means of the screw 30.

Riveted, or otherwise secured to the angle member 21, is a vertically extending spring arm 31, which cooperates with the upper end of the wing 23, to properly hold the tube frame to the chain.

It will also be noted that, by reason of the fact that the beam 10 is hollow, there will not be any tendency toward bending or warping, as is usual in beams which are generally formed from a solid strip of wood.

What is claimed is:

1. A tuft yarn carrier for a loom including a hollow beam, a spool supporting means engaged in an end of the beam, chain engaging means engaged within the beam engaging portion of the spool supporting means, the beam received portion of the spool means having openings and slots, the beam received portion of the chain means having openings alining with said slots, fastening devices disposed through the beam and the openings of the spool means, and fastening devices disposed through the beam, the said slots, and the openings of the chain means.

2. A tuft yarn carrier for a loom including a hollow beam, spool supporting means having a wing and flanges engaged in the ends of the beam, fastening means engaged through the beam and the flanges, a chain engaging means having a wing engaged in the beam and beneath the spool supporting

means and having flanges engaged between 50 the first flanges, the first flanges having openings, and fastening means engaged through the beam, the second flanges and the said openings whereby upon breakage of the second fastening means the spool 55 supporting means will not be disturbed.

3. In a tuft yarn carrier, a hollow beam, a spool supporting means and a chain engaging means engaged in each end of the beam, the spool supporting means comprising an angle plate having one wing engaged 60 in the beam and having depending flanges provided with openings and open-ended slots, the chain engaging means comprising an angle plate having one wing engaged 65 in the beam and beneath the said flanges, the last-named wing having flanges disposed between the first-named flanges and having openings aligned with the said slots, and independent fastening means engaged 70 through the beam and the openings of the spool supporting means and the openings of the chain engaging means.

4. In a tuft yarn carrier, a hollow beam, a spool supporting means engaged in an 75 end of the beam, a chain engaging means engaged in said end of the beam and interengaging with the beam engaging portion 80 of the spool supporting means, fastening devices engaged through the beam, the chain engaging means, and the spool supporting means and in securing relation to the latter only, and fastening devices engaged through the beam, the spool supporting means and the chain engaging means and 85 in securing relation to the latter only, the interengaging portions of the spool and chain means and the fastening devices therefor being constructed and arranged to permit proper or violent withdrawal of the 90 chain engaging means from the beam without displacement of the spool means.

In testimony whereof I affix my signature, in the presence of two witnesses.

EUGENE F. CLARK.
